ATTORNEY'S

UNITED STATES PATENT OFFICE.

JOHN R. SEARIGHT, OF DETROIT, MICHIGAN.

DESIGN FOR A PENCIL-SHARPENER.

46,068.

Specification for Design.

Patented July 7, 1914.

Application filed April 13, 1914. Serial No. 831,650. Term of patent 14 years.

To all whom it may concern:

Be it known that I, JOHN R. SEARIGHT, a citizen of the United States of America, residing at Detroit, in the county of Wayne and State of Michigan, have invented a certain new, original, and ornamental Design for Pencil-Sharpener, of which the following is a specification, reference being had therein to the accompanying drawings, forming part thereof, in which the figure

is a perspective view of a pencil-sharpener, showing my new design.

I claim:

The ornamental design for a pencil sharpener, substantially as shown.

JOHN R. SEARIGHT.

Witnesses:

JAMES P. BARRY,
W. K. FORD.
